UNITED STATES PATENT OFFICE.

JOHN THOMSON, OF NEW YORK, N. Y.

ELECTRIC FURNACE FOR FUSING METALS.

1,308,877.

Specification of Letters Patent. Patented July 8, 1919.

Application filed October 7, 1918. Serial No. 257,212.

To all whom it may concern:

Be it known that I, JOHN THOMSON, a citizen of the United States, and a resident of the borough of Manhattan, city of New York, county and State of New York; have invented certain new and useful Improvements in Electric Furnaces for Fusing Metals, of which the following is a specification.

10 This is an invention in electric furnaces for fusing metals, particularly non-ferrous metals and alloys thereof. The furnace as herein illustrated and described is of the resistance type.

15 The furnace which is the basis of the present invention has what may be described as a rolling motion about a vertically extending axis and this motion is herein frequently referred to as a gyratory movement. The furnace, as will hereinafter more fully appear, has a substantially horizontally extending tank or bed within which the metal, or metals, to be fused is placed and within which the fused or molten metals are held, 20 and the furnace structure is so made that when the rolling or gyrating motion is taking place a vertically extending line—preferably the vertically extending center line of the tank or bed—swings in a conical path 25 about a vertically extending axis passing through the center of a support upon which the furnace structure is carried.

30 As showing a specific embodiment of the invention reference is made to the accompanying drawings forming a part of this specification, in which drawings,

35 Figure 1 is a vertical center section, transverse as to the resistor.

40 Fig. 2 is a vertical center section, longitudinal as to the resistor.

45 Fig. 3 is a horizontal section along the zone A of Fig. 2, also denoting the resistor in plan; and

Fig. 4 is a view which illustrates the gyratory or rolling movement of the furnace.

50 The resistor B is of the type that is generally known, in common parlance of the art, as the "zig-zag" resistor. It is preferably formed from a carbon block, rod or slab and is here shown within a casing C formed of material immune to oxidization, and the design and construction of the resistor is such that the current-density progressively increases from its upper to its lower surface,

and the rate of transfer of heat through the 55 casing corresponds thereto.

From the drawings it will be observed that the longitudinally extending sides slope downwardly and outwardly. The inner end of the resistor casing rests on a refractory block D, within a niche E of the end-wall of the furnace, while the outer end is supported in the opposite end-wall and the resistor terminals F G pass through to the outside and are connected in an electric power circuit which is empirically denoted by H.

The preferred disposal of the aforesaid resistor is along what may be arbitrarily referred to as the approximate central longitudinal axis of the furnace-chamber I and above an open tank or bed J which is shown as containing a molten charge K and within which the metal is placed prior to being melted or fused. The side-walls of the furnace-chamber, to wit, the longitudinal walls which extend lengthwise of the resistor, are sloped inwardly and upwardly, as at L, Fig. 1 and support a cover or an arched roof, as M. The angle of these side-walls is a function of the angle of the sides of the resistor and its location relative to the tank, whereby the flow of heat from the sides of the resistor will be refracted from the sloped side-walls downwardly upon the surface of the bath, as is denoted by arrows a. 85 Heat from the lower surface of the resistor passes directly to the bath, as shown by arrows b. In this wise, the transfer of energy to the charge is very uniform and effective.

In fusing alloys composed of such metals as copper, zinc, lead, aluminum, etc., it is very important that the charge shall be thoroughly commingled. This is accomplished to a high degree of perfection by employing a substantially horizontally extending melting tank or bed which in plan is square or rectangular, see Fig. 3, and by so mounting the entire furnace that a gyratory movement or rolling movement about a vertically extending axis may be 100 imparted thereto. The orbit of gyration, adequate for said purpose, is quite nominal, say about 8° or so, as is shown at C, Fig. 4, in that the flow imparted to the bath is a combination of circular movement as indicated by arrow d Fig. 3, with off-shooting swirls or eddies at the corners of the tank, as indicated by arrow e. In fact, a demon-

strative model has shown that a swashing action is produced of such effectiveness that, by a few gyrations, the whole mass is as completely mixed as in the instance of pouring a fluid from one beaker to another.

A preferred manner of effecting the aforesaid gyration of the furnace is comprised in properly coöordinating the following elements: The brick-work of the movable furnace structure is mounted upon a bed-plate N having on its under side or face a plate or disk 5 of lesser diameter. The plate or disk 5 has a depending hemispherical ball 6. The said disk and ball are adapted to be sustained by a pedestal P whose upper face is formed to the frustum of a cone 7 and has a socket 8. The conical frustum and its correlated disk (or both may be frustums of cones) chiefly sustain the over-load, the ball and socket serving as a pin and socket to maintain a fixed relationship, and as the impingement of the disk and frustum closely approximates an exact rolling contact friction is reduced to a minimum. Now, when the disk is caused to make a complete orbital gyration or "oscillation" as it is at times designated, the path described by the central, vertical axis R is that of a cone. In fact, the kinematics, as a whole, has been popularly summarized as "the disk-action" and has been most largely employed in water meters. This action may properly be referred to as a rolling action about a vertically extending axis. If the angle of gyration is slight and the frustum, or frustums, accurately machined, there will be but a merely nominal tendency for the furnace to "creep" in a circulatory direction; this, however, can be readily prevented by means of a link or chain, as Ch; one end of which link or chain is secured to the casing of the movable furnace structure and the other end of which link or chain is fixedly secured in any suitable manner.

To produce a relatively slow and smooth gyration, a short spindle, as S, Fig. 1, is provided, here shown as being inserted in the crown of the arch, whose vertical center coincides with that of the vertical axis p of the furnace. Upon any suitable means of support, such as side pillars T and channel V, a gear W and pinion 9 may be mounted, to be driven as by means of a motor, chain or belt, and the lower extension of the gear-shaft 10 may carry an arm 11. Thus, when this arm is caused to revolve in a circle it will impart orbital movement to the spindle S thereby gyrating the furnace through one complete cycle for each revolution of the gear.

The next feature of correlative importance relates to such a construction of the furnace as will avoid deformation of the brick-work when the gyratory movement or rolling action is taking place, and as will

prevent infiltration of air into the heating chamber and effect heat-insulation of a high order, all of which features are realized by sheathing the outside walls of the furnace with steel sheets Y, preferably flanged, as at 70 h, and by securing them by suitable bolts to the iron bed-plate N. Instead, however, of placing the sheets in physical contact with the brick-walls a clear surrounding space is provided into which powdered fire-brick, or magnesia, or infusorial earth, or the like, as n, is tamped. Thus, if the character of the refractories is such as to expand, the powder will be the more compressed and the sheets will automatically spring outwardly; per 80 contra, if the refractories shrink additional powder can readily be inserted and tamped to compensate. In this wise, the brick-work is very rigidly held in place; no air can pass through the sheets and powder (the latter 85 serving as a "sand-joint") and the effectiveness of the heat-insulation approximates unity. Moreover, these sheets are preferably applied in two vertical series. Thus, as in Fig. 1, they also serve to take the thrust of 90 the arched cover and, as in Fig. 2, to maintain a suitable alinement of the resistor. Yet, when necessary to replace a resistor, or a tank, it is only necessary to disconnect and remove the upper series of sheets and the 95 corresponding zone of brick-work. This system of sheathing may also be advantageously applied to other types of furnaces. The aforesaid "sand-joint" may be extended to the roof of the furnace both for the purpose of diminishing the escape of heat thereat and for the exclusion of air from the interior.

The tube m, Fig. 1, may conveniently be used for the insertion of pyrometers; to introduce an inert gas within the furnace-chamber and also to exhaust vapor or air therefrom, as may be desired. In this connection, it is pointed out that by the very complete seal afforded by the sheathing and interposed powder, which acts as a "sand-joint," it is much more feasible to obtain and maintain a partial vacuum in the furnace-chamber than has been the case hitherto in electric furnace practice.

There are two important contingent advantages inherent in gyratory movement or rolling action of the furnace and the already described mode of effecting it which consists, firstly, in being able to revolve the furnace upon its ball and socket so that its charging-port X and tap-spout Z may be swung to any position most convenient for their operation; and, secondly, to so tilt and hold the furnace, when tapping off a molten charge, that the tank or bed can be rapidly emptied.

Various modifications may be made in the construction and disposal of the several dominant elements of this invention without 130

- evading the purview hereof; for example, instead of using a single centrally disposed resistor it may be formed of two limbs electrically incited in series or in parallel.
- 5 5 Moreover, in certain cases, as in the refinement of zinc by distillation, the resistor casting can then be advantageously dispensed with.
- As to the form of tank or bed, while the 10 preferred form is shown and described as being square or rectangular, it will be manifest that other forms of tank or bed might be used and still come within the purview of the broader aspects of the invention.
- 15 15 What I claim is:
1. In electric furnaces, a suspended carbon resistor disposed along a central longitudinal axis of the furnace-chamber, above an open melting tank, and longitudinally 20 extending chamber side-walls, sloping inwardly and upwardly, whereby the heat which flows from the correlated sides of the resistor is directly refracted upon the charge.
  - 25 2. An electric furnace for fusing metals contained in a tank, the said furnace being sustained by an underlying "oscillating disk action" whose axis describes a cone, the apex of which is beneath the furnace.
  - 30 3. An electric furnace for fusing metals contained in a tank, the said furnace being mounted upon an underlying "oscillating disk action" and means, located above the furnace, for imparting gyratory movement 35 to the structure.
  - 40 4. An electric furnace for fusing metals contained in a tank, the entire structure being mounted upon a sustaining pedestal with a coördinating ball and socket, a disk or plate and conical frustum producing the so-called "oscillating disk action," and extraneous means for imparting gyratory movement thereto.
  - 45 5. In an electric furnace capable of being gyrated, a fusing tank whose form, in plan, is approximately rectangular, whereby the circulatory flow of the molten metal, at the corners of said tank, is diverted into swirls or eddies.
  - 50 6. An electric furnace having a carbon resistor suspended above a melting tank, an outer casing formed of two vertically disposed series of removable steel sheets, a space between the said sheets and the fur-
- nace-walls which is filled with powdered material, and interior brickwork of a character which expands when heated.
7. A furnace for fusing metals having a furnace structure mounted upon a support in such a manner that there can be imparted 60 to the furnace structure a gyratory movement or rolling action about a vertically extending axis of a character whereby a vertically extending axis of the furnace structure moves in a conical path to said vertically extending axis of the support, and means for imparting to the furnace structure said movement, the furnace structure being provided with a substantially horizontally extending tank or bed for holding 70 molten metals and a substantially horizontally extending resistor located in the furnace above said tank or bed.
8. A furnace structure mounted upon a suitable support in a manner to permit a 75 gyrating movement to be imparted to the furnace structure, and means for imparting to the furnace structure said gyrating movement, the furnace structure having therein a square or rectangular shaped tank or bed 80 within which molten metal is contained.
9. A furnace structure mounted upon a suitable support and means for moving the furnace structure so that a vertically extending line of the furnace structure moves in 85 a conical path about a vertically extending axis which passes through the point of support, the furnace structure having a horizontally and longitudinally extending resistor with side-walls which slope down- 90 wardly and inwardly, which resistor is contained within a chamber of the furnace structure that is provided with longitudinally extending side-walls which slope upwardly and inwardly, the furnace structure 95 having therein a substantially horizontally extending tank or bed which is rectangular in plan and above which tank or bed said resistor is located, the side-walls of said chamber being arranged so as to deflect heat 100 transferred from the sides of the resistor to metal contained in the tank or bed.

This specification signed and witnessed this first day of October, A. D. 1918.

JOHN THOMSON.
